UNITED STATES PATENT OFFICE.

WILLIAM JOHN WITKUS, OF MASPETH, NEW YORK.

DRAWING DEVICE.

Application filed January 28, 1928. Serial No. 250,197.

The invention relates to drawing devices, which, in my case, is with an elastic or wire spring band on which a drawing guide is operated in conjunction with a slotted straight edged rule or measuring and ruling tool or either independently and the objects of the invention are, first, to provide a handy device for making accurate enlargements; second, to provide means for making grotesque enlargements; and, third, to afford facilities for the proper adjustment of drawing guide according to the size of enlargement desired for either accurate or grotesque enlargements.

One form of the invention is illustrated in the accompanying drawing, in which Figure 1 is a plan view of the entire drawing device; Fig. 2, is a vertical section of the entire device; Fig. 3, is a plan view of the drawing guide connected up for operation without slotted tool; Fig. 4, is a vertical view of one side of the drawing guide; and Fig. 5, is a perspective view of the complete drawing device in operation.

The slotted tool 4 with the idling pins 6 6, its writing hole 7, the adjustable drawing guide 1 on the elastic band 2, with one of its connections in the screw-eye 5 and the other on the pivot-tack 3 constitute the complete drawing device.

The slotted tool 4 in conjunction with the drawing guide 1 gives the added advantages of measuring off size of enlargement desired, ruling straight lines when necessary and giving greater steadiness while drawing.

The drawing guide 1 with elastic band 2, pencil 8 and pivot-tack 3 may be used independently of the slotted tool 4, though without the added advantages of measuring, ruling and steadiness.

The slotted tool 4 may be used with the drawing guide 1 on the elastic band 2 and its connections, one in the screw-eye 5 and the other on the idling pins 6 6, with the pivot-tack 3 free, thus eliminating the full operation of the elastic band 2, with the result of distortion or grotesqueness in the copied drawing, the distortion varying with each change of the position of the picture to be copied.

For correct enlargements, the best position for the picture to be copied is on a horizontal line with the pivot-tack 3 and within the limits of drawing guide 1. In this position the drawing guide 1 is guided over picture to be copied by holding writing implement 8 and operating it with the guidance of and in coordination with the drawing guide 1. Thus the picture is reproduced by the writing implement 8.

I am aware that prior to my invention drawing devices, such as the pantograph, have been made, but none with the unique and novel arrangement and originality of this invention wherein the adjustable drawing guide, and elastic or wire spring band in conjunction with the slotted tool or either independently swings on a pivot and works back and forth by the aid of the elastic or spring band, and the slotted opening runs on the same pivot much as the driving wheel of an engine.

I claim as new and desire to secure by Letters Patent:—

1. A drawing device comprising a part having a longitudinal slot therethrough and being adapted for ruling and measuring, securing means on said part adjacent one end of said slot there being a scribe-receiving hole adjacent said means, a pivot tack adapted to be received in said slot whereby the part may pivot and slide relative thereto, an elastic element having one end secured to said securing means and the other to said pivot tack, and a drawing guide releasably connected to said elastic element.

2. A drawing device comprising a part having a longitudinal slot therethrough and being adapted for ruling and measuring, securing means on said part adjacent one end of said slot there being a scribe-receiving hole adjacent said means, a pivot tack adapted to be received in said slot whereby the part may pivot and slide relative thereto, a spring element having one end secured to said securing means and the other to said pivot tack, and a drawing guide releasably connected to said spring element.

WILLIAM JOHN WITKUS.
